A. DAVIS, JR.
COMBINED TANK AND CABINET.
APPLICATION FILED JAN. 8, 1917.

1,248,088.

Patented Nov. 27, 1917.

UNITED STATES PATENT OFFICE.

AUGUSTINE DAVIS, JR., OF COVINGTON, KENTUCKY.

COMBINED TANK AND CABINET.

1,248,088.

Specification of Letters Patent. Patented Nov. 27, 1917.

Application filed January 8, 1917. Serial No. 141,173.

To all whom it may concern:

Be it known that I, AUGUSTINE DAVIS, Jr., a citizen of the United States, and a resident of Covington, in the county of Kenton and State of Kentucky, have invented certain new and useful Improvements in Combined Tanks and Cabinets, of which the following is a specification.

My invention relates to tanks, especially 10 those mounted on trucks or wagons. The object is to combine with the tank a suitable cabinet or "bucket-box" on one end of the tank, generally the rear end, in such a manner that this cabinet will not become 15 loosened from the tank or have its component parts loosened from each other under the severe racking sustained incident to the travel of the vehicle.

My invention consists in the combination 20 of parts and in the details of construction and arrangement of parts as will herein-after be more fully described and claimed.

In the drawings:

Figure 1 is a rear elevation of a structure 25 embodying my invention;

Fig. 2 is a vertical longitudinal section on a plane corresponding to the line 2—2 of Fig. 1, only part of the tank being shown;

Fig. 3 is a vertical cross section on a plane 30 corresponding to the line 3—3 of Fig. 2, looking toward the cabinet;

Fig. 4 is a similar cross-section but showing a modification; and

Fig. 5 is a partial section corresponding 35 to Fig. 2 but enlarged to better show the attachment of the rear head of the tank, and of the cabinet, to the tank.

The bucket-box, which is for the purpose 40 of holding cans or measuring vessels or buckets, has heretofore been made separate from the tank and mounted on a rear extension of the frame work of the wagon or truck or of the mounting of the tank; and usually has been made principally of wood.

Such a bucket-box soon becomes loosened 45 from its mounting and its parts become loosened from each other in a short time under the jolts and strains incident to the travel of the truck or wagon. The wooden 50 bucket-box becomes oil-soaked and its screws and bolts become loosened. The paint cracks and comes off the wooden box, so that both the usefulness and appearance of the bucket-box are greatly impaired after a 55 short period of use.

My invention is more intimately concerned with the kind of tank that has the

shell and a rear head, as well as other parts not shown herein, joined together by welding, which is preferably done by means of 60 the oxy-acetylene process. Thus, as shown in the drawing, the shell 1 of the tank has the head 2 which has the peripheral annular flange 3 and, in the process of welding, becomes concavo-convex or "dished" in the 65 direction opposite to that in which the flange 3 extends. Ordinarily, such a head is put into the end of the shell with the flange 3 extending into the shell so that the convex side of the head will be outward. However, 70 in carrying out my invention, the head is placed in the shell with the flange 3 projecting outward; that is to say, it is "backed" in. Moreover, the outer edge of the flange is not left flush with the end of the shell; 75 the head 2 is located somewhat farther inward so that there is some projection of the shell 1 past the flange 3 as is seen in Figs. 2 and 5.

I construct the bucket-box mainly of the 80 same material that the tank is constructed of, i. e., steel plate. In this construction there is a shell 4 that forms the top, sides and bottom of the box, and a head 5 and head 6 having their edges welded, preferably 85 in the manner above alluded to, to the opposite edges of the shell 4. Preferably, as this structure is first produced, both the heads 5 and 6 are continuous sheets; so that the box, when the welding just alluded to 90 has been completed, is completely closed on all sides. However if the box is largely of the same cross-section as the tank as shown in Figs. 1, 2 and 3, the head 5 is not provided complete, but there is provided only 95 a small part of ample area to cover such part of the box as will not come within the limits of the rear of the tank. If the box is of considerably greater cross-section than the tank, its top is preferably extended 100 above the top of the tank, as shown in Fig. 4; in which case the head 5' is made complete across the end of the box the same as the head 6 is.

In any case, either the continuous or the 105 partial head 5' or 5 is then cut to have an edge conforming fairly accurately to the rear end of the tank shell. If part of the box shell 4 conforms to the corresponding part of the tank shell 1 as the upper part 110 in the example of Figs. 1 to 3 does, this part of the box shell 4 and the edge of the box head, cut as above described, constitutes a continuous abutment against the rear end of

the tank shell 1, which has been left projecting past the flange 3 of the tank head 2 as before described. With these parts thus abutting, they are welded together, preferably by the process above alluded to, so that the entire bucket-box and the shell 1 and head 2, and indeed all of the other welded-together parts of the tank not shown herein, form an integral piece of steel.

10 The other head 6 has a door opening 7 cut in it, preferably of relative size and shape about as illustrated in Fig. 1; really leaving only a small part of the original head 6 welded to the box shell all around this end, 15 which reinforces this end of the shell of the bucket-box.

10 The cutting of both heads 5 or 5' and 6 is preferably done by means of an oxy-acetylene cutting torch. It is more desirable to 20 thus weld the head 5' and 6 or partial head 5 to the respective ends of the box shell 4 before cutting away any of their interior parts. When the head is continuous, as is the head 5 or the head 6, it is then less distorted in the 25 process by unequal expansion and contraction in different parts of the sheet, which are not unavoidable with the most careful performance of the welding process. Where only part of the head is provided, the fitting 30 of the edge of this part to the corresponding part of the rear end of the tank shell 1 will be more accurate if it is done after the welding operation, and after such distortion as is produced in the welding process has taken 35 place and the part of the head has permanently assumed this distortion. Also, the opposite head 6 helps to maintain the shape 40 of the bucket-box shell 4, against the distorting influences while the bucket-box is being welded to the tank.

I reinforce this tank rear head 2 by part of the wooden structure which is built inside the steel outer structure of the bucket-box. The bucket-box faces as does the rear of the 45 tank, but for clearness, the part next to the tank will, in the following description, be treated as the back of the box. Thus, preferably, I place upright battens of studding 50 8 in the concavity of the rear end of the tank, which have their adjacent edges curved to fit the concavity of the head 2, and which have their other edges toward the front of the box, straight and extended far enough past the rear end of the tank to receive 55 the transverse boards 9, which have their ends fitting closely against the interior of the box shell 4 all around, and which are fastened to the battens or studding 8 and form the back lining of the box. In front 60 of these boards 9 I provide a shell lining comprising a wooden bottom or floor lining 10, resting on the bottom of the shell 4, and wooden side linings 11 with their lower ends against the end parts of the floor 10, close 65 against the interior side walls of the shell 4;

and where the box has the curved top, as shown in the drawing, preferably terminating where the curve of the top begins, and there receiving a transverse wooden shelf 12 which preferably has in it partitions 13 running down to the floor 10, dividing the lower part of the bucket-box into a suitable number of compartments. Preferably angle irons 14 reinforce the attachment of these partitions 12 to the floor 10 and the shelf 12 above as well as the shelf to the side linings 11. The curved top above the shelf 12 is preferably left unlined. Thus the entire lower part of the box is lined with wood and the bottom and back of the upper compartment are of wood. This lessens the noise of rattling of the articles placed in the box during travel of the vehicle. The floor 10, sides 11, shelf 12 and partitions 13 all abut closely against the back boards 9 and against the front head 6 of the bucket box, so that this entire wooden structure forms a reinforcement for the tank head 2.

A wooden casing 15 is bolted on the outside of the head 6 all around the door opening 7, and of such width relative to the remaining parts of the head 6 that a ledge 16 is left all around the door opening against which the door closure 17 abuts; this latter preferably being hinged to the upper part 95 of the casing and opening upwardly and being provided with a suitable fastening means 18 in its lower part to engage with the edges of the door opening. This closure 17 is preferably made up of a wooden frame 100 19 inclosing a thin steel panel 20, and also reinforced by the battens 21 on the inside; the middle part of the front edge of the shelf 11 being cut away to make room for these battens 21 when the door is closed. A 105 steel band 22 is placed all around the front end part of the bucket-box, covering the edge of the door casing 15 and the adjacent part of the bucket-box shell 4 and being suitably secured to said door casing and to said shell. 110 This band gives a finished appearance to the structure, and not only reinforces the connection of the door casing of the steel part of the bucket-box, but further reinforces the bucket-box shell 4 and its connection to the 115 head 6 at this end. Suitable jointed braces 23 at the sides hold the door 17 in raised open position.

From the description just given, it will be seen that the only wooden parts of the exterior of the bucket-box are the door casing 15 and door frame 19. Thus, not only is the bucket-box of integral steel construction integral with the tank, to protect the rear of the tank, to remain in position, and to hold 125 together under the severe strains of vehicle travel; but it is possible to apply and maintain a much better finish on the metal surface than upon a wooden surface.

Having fully described my invention, what 130

I claim as new and desire to secure by Letters Patent is:

1. A tank comprising a sheet metal head, and a sheet metal shell attached to and projecting past said sheet metal head with its edge exposed, and a cabinet comprising a sheet metal shell and a sheet metal head part, with said head part integral with said exposed edge of said shell of said tank.
- 10 2. A tank comprising a sheet metal head, and a sheet metal shell attached to and projecting past said sheet metal head with its edge exposed, and a cabinet comprising a sheet metal shell and a sheet metal head part, with part of its shell and said head part integral with said exposed edge of said shell of said tank.
- 15 3. A sheet metal tank, and a sheet metal cabinet comprising a sheet metal shell with one end secured to the end of said tank, said shell of said cabinet extending out from said tank whereby its opposite end is not directly supported by said tank, and means extending around near said opposite end of said shell of said cabinet, reinforcing said end of said shell.
- 20 4. A tank comprising an integral sheet-metal shell and sheet-metal head, and a cabinet comprising an integral sheet-metal shell and sheet-metal head part, with said head part integral with said shell of said tank, a batten abutting the outer surface of said head of said tank, and a lining secured to said cabinet against said batten to reinforce said head of said tank.
- 25 5. A tank comprising an integral sheet-metal shell and sheet-metal head and a cabinet comprising an integral sheet-metal shell and sheet-metal head part, with said head part integral with said shell of said tank, a back lining in said cabinet and having means against said head of said tank, a shell lining for the shell of said cabinet abutting said back lining, and means on said cabinet holding said shell-lining against said back lining.
- 30 6. A tank comprising a sheet-metal shell and sheet-metal head and a cabinet comprising an integral sheet-metal shell and sheet-metal head part, said head part being secured to said shell of said tank, a back lining in said cabinet and having means against said head of said tank, a shell lining for the shell of said cabinet abutting said back lining, an opposite head secured to said shell of said cabinet, and having a door opening, and abutting and holding said shell lining against said back lining.
- 35 7. A tank comprising a sheet-metal shell, a sheet-metal head having a peripheral annular flange, and welded in said shell with its flange extending outwardly of said shell

but spaced inward from the end of the shell, a sheet-metal cabinet comprising an integral sheet-metal shell and sheet-metal head part 65 with said head part welded to said end of said shell, a batten abutting the outer surface of said head of said tank, and a lining secured in said cabinet against said batten to reinforce said head of said tank.

8. A tank comprising a sheet-metal shell, a sheet-metal concavo-convex head having a peripheral annular flange extending from its concave side, and welded in said shell with its convex side inwardly the shell and 75 its flange extending outwardly of said shell but spaced inward from the end of the shell, a sheet-metal cabinet comprising an integral sheet-metal shell and sheet-metal head part with said head part welded to said end of 80 said shell, a batten abutting and conforming to the outer concave surface of said head of said tank, and a lining secured in said cabinet against said batten to reinforce said head of said tank.

9. A tank comprising a sheet-metal shell, a sheet-metal concavo-convex head having a peripheral annular flange extending from its concave side, and welded in said shell with its convex side inwardly of the shell 90 and its flange extending outwardly of said shell but spaced inward from the end of the shell, and a sheet metal cabinet comprising an integral sheet-metal shell and sheet-metal head part with part of its shell and part of 95 said head part welded to said end of said shell, a batten abutting and conforming to the outer concave surface of said head of said tank, a back lining secured to said batten in said cabinet, and a shell lining 100 for the shell of said cabinet abutting said back lining, and means on said cabinet holding said shell lining against said back lining.

10. A tank comprising a sheet-metal 105 shell, a sheet-metal head having a peripheral annular flange, and welded in said shell with its flange extending outwardly of said shell but spaced inward from the end of the shell, and a sheet-metal cabinet comprising 110 an integral sheet-metal shell and sheet-metal head part with said head part welded to said end of said shell, a batten abutting said head of said tank, a back lining secured to said batten in said cabinet, and a shell 115 lining for the shell of said cabinet abutting said back lining, and means on said cabinet holding said shell lining against said back lining.
